UNITED STATES PATENT OFFICE.

ANNIBALE N. DE RUBERTIS, OF WATERBURY, CONNECTICUT.

SKIRT MARKER.

Application filed April 25, 1922. Serial No. 556,472.

To all whom it may concern:

Be it known that I, ANNIBALE N. DE RUBERTIS, a citizen of the United States, and a resident of Waterbury, county of New Haven, and State of Connecticut, have invented certain new and useful Improvements in Skirt Markers, of which the following is a specification.

This invention relates to skirt markers and more particularly to a device to be used by dress-makers and ladies' tailors for marking the bottom portion of a skirt while the wearer is standing in an upright position.

One object of the invention is to provide a skirt marker in which the marking device, such as chalk or crayon may be adjustably secured in any desired vertical position with respect to the skirt.

A further object is to provide a device of this nature in which the chalk holder is flexibly mounted upon a vertical standard in such a manner that the chalk may be moved in a straight line.

A further object is to provide a skirt marker which may be slid up and down upon a vertical rod and adjustably clamped upon said rod in any desired position.

A further object is to provide a skirt marker in which the marking device is slideable upon a vertical standard, and which comprises three pivoted members, one for clamping it to the standard, one for holding the marking chalk, and an immediate link for flexibly pivoting the other two members together.

A further object is to provide a skirt marker which will be simple, cheap to manufacture, easy to manipulate, and very efficient and durable in use.

With these and other objects in view there has been illustrated in the accompanying drawings one form in which the invention may be conveniently embodied in practice.

Fig. 1 is a perspective view, on a reduced scale, showing the skirt marker as it appears when being used upon a skirt.

Fig. 2 is a perspective view of the skirt marker.

Fig. 3 is a bottom sectional view of the skirt marker the section being taken through the standard and scale below the marking member.

Fig. 4 is a side view, partly in section, of the slideable marking member.

55 In the use of previous skirt marking de-

vices, considerable difficulty has been experienced in tracing an even line upon the dress. This was due to the fact that the chalk-clamping members were generally pivoted to a stationary member, and the chalk was therefore constrained to move only in the arc of a circle. Consequently the chalk as it moved in its circular path was at a variable distance from the dress and its support. With such devices, only a series of separated dots or short lines could be made on the skirt.

In order to secure a continuous line with such previous skirt marking devices, it was customary for the operator during the marking process either to bend the vertical standard toward the supporting scale, or else to twist the rod clamping member about the rod. As will be evident, both of these methods were quite injurious to the apparatus. In the first instance, the rod was apt to become permanently bent or even broken off from its base; in the second instance, the rod clamping member had a tendency to slip down upon the rod and thus impair the accuracy of the marking.

By means of the present invention the above and other disadvantages have been largely if not entirely avoided. This has been accomplished by providing an additional connecting link between the rod clamping member and the chalk holder in such a manner that the chalk may be freely moved in a straight path instead of only in a curved path as before. In this manner an even and continuous mark will be obtained and the danger of breaking the rod or of having the chalk-holder slip downwardly with respect to the scale is avoided.

Referring now to the drawing in which like reference numerals denote corresponding parts throughout the several views, the numeral 10 represents a horizontal base having one end split, as shown in Fig. 2, forming side legs 11 and 11^a. The base 10 is also provided with an elongated central aperture 12 which results in a considerable reduction of weight of the base without materially diminishing its strength.

Extending upwardly from the rear of the base is a vertical back-rest 13 preferably constructed from a thin strip of sheet metal, having parallel sides, and with its edges rounded slightly at the top. This back-rest 13 may be provided with a scale having any

desired graduations. In the illustrated embodiment of the invention the scale is provided with a series of short lines of varying length, representing inches, half inches, and quarter inches respectively.

While the scale shown extends only from 1 to 12 inches, it will be understood that the length of the scale and back-rest 13 may be varied as desired, according to the length of 10 the skirt to be marked.

For securing the scale 13 rigidly in position at the rear of the base 10, a vertical bracket or scale support 14 is provided. This bracket 14, which is preferably formed 15 integral with the base, is perforated near its top to receive a screw 15, said screw also passing through a registering screw hole in the back-rest, whereby the bracket and back-rest will be firmly united. In order to hold 20 the bottom of the back-rest firmly against the bottom of the bracket 14, a recess 16 is formed in the rear end of the base 10, in which the back-rest 13 is adapted to rest, as clearly shown in Fig. 2.

25 In order to form a slidable support for a marking member, the forward part of the base 10 between the split section and the aperture 12 is provided with a vertical standard 17 spaced from and parallel to the back-rest 13 in any suitable manner. The standard 17 extends substantially to the same height as the back-rest 13 and is preferably cylindrical in section although if desired it may be formed rectangular or of 30 any other suitable section.

The slidable marking member which is clearly shown in Figs. 2 to 4, comprises a forward U-shaped clamping collar 18, an intermediate link 26, and a chalk-holder. 40 The collar 18 is preferably formed by casting from iron or other suitable metal and is provided with a pair of resilient spaced vertical arms 19 and 20, adapted to grip the standard 17 securely in any desired adjusted 45 position when the wing-nut 21, threaded into said arms 19 and 20, is tightened. A washer 21^a is preferably located between the wing-nut 21 and the side arm 19. The clamping collar is also provided with a pair of horizontal spaced ears 23 and 24 forming a bearing 50 for a vertical pin 25, upon which the forward end of a connecting link 26 is pivoted.

The connecting link 26 is preferably 55 formed from a solid piece of metal of rectangular section and has its free end perforated to receive a pintle 26^a, upon which a pair of opposed chalk-clamping jaws 27 and 28 are pivoted. The jaws 27 and 28 are arched 60 slightly at their central sections 29 and 30, as clearly shown in Fig. 4, and have their

tips 31 and 32 bent toward one another to grip the chalk or crayon 33.

As most clearly shown in Fig. 4, the central arched portions 29 and 30 of the clamping jaws 27 and 28 are provided with aligned apertures to receive an adjusting screw bolt 34 having a head 35 at its lower end and carrying a knurled finger nut 36. A helical spring 37 which is mounted on the screw bolt 34 between the jaws 27 and 28 exerts continuous pressure upon said jaws 27 and 28, tending to force them apart.

In operation when it is desired to mark a skirt to indicate where it is to be trimmed off 75 so that it will hang at a uniform distance from the floor, the marking member is first adjusted on the standard 17 by means of the scale on the back-rest 13 according to the height of the skirt desired. The device is 80 then set upon the floor beside the person wearing the skirt. The operator then moves the device, step by step around the person, with the back-rest 13 behind the skirt to serve as a support for the chalk, and at the 85 same time moving the chalk back and forth so that a continuous mark will be made around the entire circumference of the skirt in the same horizontal plane. After the skirt has been thus marked, it may be removed from the wearer and trimmed to the proper length.

It will be understood that the invention may be employed not only for marking skirts but also for the marking of coats, 95 dresses, or any other article of wearing apparel.

While there has been disclosed in this specification one form in which the invention may be embodied, it is to be understood 100 that this form is shown for the purpose of illustration only, and that the invention is not to be limited to the specific disclosure but may be modified and embodied in various other forms without departing from its 105 spirit. In short, the invention includes all the modifications and embodiments coming within the scope of the following claim.

Having thus fully described the invention, what is claimed as new, and for which it is 110 desired to secure Letters Patent, is:

In a skirt marker, a base, a vertical standard, a standard clamping member mounted on said standard, a link pivotally connected to said standard clamping member, a chalk 115 clamping member pivoted to said link, and means adapted to lie behind the skirt to be marked to form a back-rest for said chalk while marking the skirt.

In testimony whereof, I have affixed my 120 signature to this specification.

ANNIBALE N. DE RUBERTIS.
